Attorney.

UNITED STATES PATENT OFFICE.

FRED A. WIGGIN, OF LAWRENCE, MASSACHUSETTS.

X-RAY TUBE.

1,218,026.

Specification of Letters Patent.

Patented Mar. 6, 1917.

Application filed October 5, 1916. Serial No. 123,943.

To all whom it may concern:

Be it known that I, FRED A. WIGGIN, a citizen of the United States, and resident of Lawrence, in the county of Essex and State 5 of Massachusetts, have invented an Improvement in X-Ray Tubes, of which the following description, in connection with the accompanying drawings, is a specification, like letters on the drawings representing like parts.

My present invention relates to improvements in targets for X-ray tubes and the object of the invention is to improve and perfect X-ray targets, and especially to enable 15 them to better withstand higher powered apparatus than those now in use; and it is also an object to devise a simple process of constructing such targets.

In the use of an X-ray tube the heat generated by the cathode stream raises the temperature of the target so rapidly that unless it were immediately diffused and conducted away, the receiving surface of the target would be fused, even if made of a 20 most refractory metal, and it has heretofore been very difficult to provide an efficient and satisfactory target and maintain its radiating surface against the cathode stream of the electric current focused on the target.

Such target must have a refractory face to withstand the intense heat there developed, which face must be connected by a perfect 25 mechanical, physical, electrical and thermal contact to a good heat conductor of sufficient mass to carry away from the radiating surface the heat as developed, so as to prevent the surface from actually becoming fused by the heat and pierced by the cathode stream focused thereon. To meet the exacting 30 conditions of such work, platinum or metals of the platinum group have been used for the reflecting surface and a copper backing has been welded or fused onto the platinum surface for heat conduction, actually 35 forming the two materials into an integral structure and in the absence of any extraneous uniting substance. Such a plate thus formed might then be united in any desired manner to a further backing substance.

Such a construction is shown by U. S. Patent No. 1,002,390, issued Sept. 5, 1911, but it has been found that such platinum targets would not stand up for long or practical use with high powered apparatus. Subsequent to the issue of said patent, efforts were 40 made to use tungsten as the refractory ma-

terial for the surface of the targets, uniting it in direct mechanical, physical and thermal contact with a copper backing. Although tungsten had been well known as a highly refractory material, yet it had never been actually utilized for X-ray tubes until recently, owing to the extreme difficulty of handling and working this material.

In the case of attaching tungsten directly 45 to a copper backing, however, the difference in the co-efficients of expansion between the two metals in the intense heat of an X-ray target caused the tungsten to separate from the copper and drop away from 50 it entirely, thus eliminating the heat-conducting function of the copper and destroying the efficiency of the X-ray tube. Furthermore, tungsten could not be united to a silver backing or the like which had 55 such a low melting point in comparison to tungsten that, under the heat generated in use in targets, not only would the tungsten drop off, but the volatilized silver would 60 blacken up the X-ray tube and destroy the 65 efficiency of the entire apparatus, and repeated experiments along these lines failed 70 to produce a satisfactory commercial article. As tungsten is a very expensive material, 75 besides being difficult to work, it is desirable, 80 if possible, to utilize a small amount of tungsten for the surface, rather than to 85 make the target entirely of tungsten.

I have discovered that by using tungsten, 90 preferably as a small button or insert for the reflecting surface of the center of the target, fitting the same into a corresponding recess in a suitable backing material, such as copper, and covering the back and sides 95 of the tungsten button with a metal capable of a degree of expansion intermediate that of tungsten and copper and of a fusion point intermediate that of tungsten and copper, a construction is obtained whereby 100 there is a suitable "give and take" to prevent separation of the several metals. Such an intermediate metal must also be capable of firmly unifying the tungsten and copper to obtain the advantages of the heat conduction so necessary. For this intermediate 105 substance I find that a metal, such as nickel, iron, Monel metal, or their equivalents, is preferable, each one named fulfilling these demands in all ways. Furthermore, this construction permits a relatively simple 110 method of building such a composite target and eliminates the necessity for the expen-

sive and difficult process heretofore necessary where the tungsten itself was fused or welded direct to the copper back.

In carrying out my invention I may provide the tungsten button with a covering at its rear and sides of nickel, iron, or such similar metal, having an intermediate coefficient of expansion and a fusion point between tungsten and copper, then uniting the button to the copper backing and supplying sufficient heat and pressure to thoroughly unify the intermediate binding metal with the tungsten on the one surface and the copper on the other surface; or such a covering may, of course, be applied to the copper surface or both if desired. While any suitable method of applying such intermediate metal may be employed, I find that it is feasible, in the use of nickel, for example, to plate a coating directly on the back and sides of the tungsten button. While I prefer to make this target with a button construction covered both on the back and sides, and insert the same in a recess in the copper backing, it is, of course, feasible to similarly attach a plate on the copper backing without inserting it therein. I have found that this construction produces a target which will permit the use of a cathode stream of higher intensity, without separation of the receiving and conducting metals, than is possible with any existing composite target.

Referring to the drawings illustrating my improved target construction,

Figure 1 is a diagrammatic view, partly in cross-section, of the X-ray tube;

Fig. 2 is an enlarged cross-sectional view showing the button construction; and

Fig. 3 is a similar view in cross-section illustrating the plate construction.

Referring to the drawings, an X-ray tube of standard construction is designated at A, having the two customary terminals therein, comprising the cathode B and the target C, the target being of usual form. The target C comprises a mass of copper C', constituting the backing and support for the face D, which, as shown in Fig. 2, is a thin button of tungsten with its intermediate binding metal E, set in a suitable recess X, formed within the backing C' and preferably of appropriate depth to enable the surface of the tungsten D to be flush with the face K of the portion C', thus constituting a target having a substantially perfect thermal connection from the target surface D on which the rays are focused to the copper backing C'.

In Fig. 3 I have illustrated the invention in a modified form having the copper backing H and the tungsten plate F united directly thereto by the intermediate binding metal G.

It will be appreciated that a relatively

thin covering of the intermediate metal will operate in the several capacities of uniting and binding the tungsten and copper in the necessary firm and thermal contact for heat conductivity, while also affording the necessary medium to allow for the "give and take" or resiliency demanded by the differences in the expansion of the tungsten surface and copper backing.

While I have referred to tungsten, it will be understood that I may use tungsten or any of its alloys, platinum, iridium, tantalum, or other metals of the platinum group and its alloys, and while I have also referred to the member C' as of copper, it will be understood that an equivalent metal may be substituted therefor, or bronze, copper composition, or the like, such backing being usually now made of copper because of its electrical and heat conductive qualities and reasonableness in price for this purpose.

My invention is further described and defined in the form of claims as follows:

1. An X-ray target, comprising a face of highly refractory metal, a backing metal of relatively high heat conductivity, and an intermediate metal or alloy having a co-efficient of expansion intermediate that of the refractory metal and said backing. 95

2. An X-ray target, comprising a face plate of highly refractory metal, a backing metal of relatively high heat conductivity, and an intermediate metal or alloy having a co-efficient of expansion intermediate that of the refractory metal and said backing, said intermediate metal constituting a binding medium between the refractory metal and said backing and being of sufficient extent to allow for the differences in expansion 100 of the said refractory metal and said backing during use.

3. An X-ray target comprising a face plate of tungsten, a backing metal of relatively high heat conductivity, and an intermediate metal or alloy having a co-efficient of expansion intermediate that of the tungsten and said backing. 110

4. An X-ray target comprising a face plate of tungsten, a backing metal of relatively high heat conductivity, and an intermediate metal or alloy having a co-efficient of expansion intermediate that of the tungsten and said backing, said intermediate metal constituting a binding medium between the tungsten and said backing and being of sufficient extent to allow for the differences in expansion of the tungsten and said backing during use. 120

5. An X-ray target comprising a face plate of tungsten alloy, a backing metal of relatively high heat conductivity, and an intermediate metal or alloy having a co-efficient of expansion intermediate that of the tungsten alloy and said backing. 125

6. An X-ray target comprising a face of highly refractory metal, a backing metal of relatively high heat conductivity, and an intermediate binder of nickel, having a co-efficient of expansion less than that of copper and greater than that of the refractory metal.

7. An X-ray target comprising a face of tungsten, a backing metal of relatively high heat conductivity, and an intermediate binder of nickel, having a co-efficient of expansion less than that of copper and greater than that of tungsten.

8. An X-ray target, having a face of

highly refractory metal, a backing metal of relatively high heat conductivity, and an intermediate metallic substance having its fusion point and co-efficient of expansion intermediate that of the refractory metal and said backing.

In testimony whereof, I have signed my name to this specification, in the presence of two subscribing witnesses.

FRED A. WIGGIN.
